GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SWITCH HANDLE.

Application filed April 8, 1922. Serial No. 550,816.

My invention relates to switch handles, and particularly to handles for rotary snap switches. The object of my invention is to provide such a connection between the handle and the switch spindle that while the operative engagement between these members is maintained, axial adjustment of the handle on the spindle is possible.

In the accompanying drawings—

10 Fig. 1 is a plan view of a rotary snap switch to which a handle embodying the present invention is applied;

Fig. 2 is a broken side elevation of the same;

15 Fig. 3 is a similar view of the handle element drawn to a larger scale and showing it in outwardly adjusted position on the spindle;

Fig. 4 is an inverted plan of the switch handle detached;

20 Fig. 5 is a broken vertical section through portion of a handle of modified construction; and

Fig. 6 is a partial sectional perspective 25 of a modified detail.

The present handle may be applied to rotary switches of various types, the particular nature of the switch mechanism, or of the switch installation as a whole, forming no part of my invention. As here indicated, the switch is of the surface type, and comprises an insulating base 6, upon which the switch mechanism is mounted and encased within a switch cover 7 of the usual 30 type. Rising through the top of the latter is the switch spindle 8, which terminates in a threaded stud 9. The switch handle comprises a hub member 10 of insulating material, with lateral pointer 11 overlying 35 the upper face 12 of the switch cover, and registering with the legends 13 which indicate the position of the switch mechanism.

40 The connection between the handle and the spindle is two-fold,—first, an operating connection for rotating the switch spindle, and thus to actuate the switch mechanism, and second, a detaining connection for holding the handle on the spindle.

45 The operating connection between the handle and the spindle is attained by a laterally projecting pin 14, rigid with the switch spindle 8 and engaged in the slot 15 in the hub of the switch handle. The slot 15 opens 50 to the well 16 in the hub which accommo-

dates the spindle 8. The well 16 and slot 15 are of such depth that a considerable latitude of axial adjustment of the handle on the spindle is possible while the operating engagement between the parts is maintained.

55 The detaining engagement between the handle and the spindle is effected by a ferrule 17 tapped to receive the threaded stud 9 of the switch spindle and swivelling with respect to the switch handle. A convenient mounting of the ferrule in the switch handle, 60 when the latter is of porcelain, is indicated in Fig. 3. The hub of the handle is pierced in register with the well 16 and shouldered at 18 and 19. The inner end of the ferrule is spun over the shoulder 18, while the head 65 20 of the ferrule overlies the shoulder 19, from which it is spaced by a take-up spring 21. A cross slot 22 in the head of the ferrule receives a screw driver for rotating it.

70 To attach the handle it is merely necessary to position the same with its slot 15 in register with the pin 14 of the spindle, and screw down the ferrule 17 on the stud 9 until the desired spacing of the inner face 75 of the hub of the handle from the face 12 80 of the switch cover 7 has been reached.

85 A connection of this general type between the switch handle and spindle is especially desirable in electrical range installations in which the switch handles overlie castings 90 which are often uneven or rough. Where a gang of switches is mounted beneath such a face plate, it not infrequently happens that although the switches may be mounted on a perfectly flat supporting bridge, the projection of the spindles through the face plate is unequal, owing to lack of planity 95 of the latter. A different positioning of the several switch handles on their spindles is therefore necessary in order to obtain a proper clearance between the handles and the face plate. The present device permits 100 such adjustment to be readily and accurately made, without disturbing the pin and slot operating connection between each handle 105 and its spindle.

110 Where the handle is used on a surface switch of the type illustrated, a cover-depressing spring washer or the like (not shown) would ordinarily be interposed between the handle and the surface of the cover to maintain the latter firmly on the base 6. It is obvious that the spring 21

has no such function, its service being merely to insure a snug engagement between the ferrule and the insulating body of the handle, and to take up such variations in size or shape of the porcelain as are commonly incident to the manufacture of handles of this material.

Where the handle is molded from bakelite, composition or other material which can be accurately shaped, the spring 21 may be omitted, as illustrated in Fig. 5. In this case, the head 23 of the ferrule bears directly against the shoulder 19. In this view I have also indicated a further modification in which the ferrule is solid, and is provided with a threaded stud 24, which takes into a tapped socket 25 in the upper end of the spindle 26. The connection between the spindle and the handle is in other respects substantially identical with that above described.

While I have shown a pin and slot operating connection between the handle and spindle, this connection may be established in other manners. One obvious variation is a flat sheared from the upper end of the spindle 8 or 26, the well 16 being correspondingly shaped, or a plural-sided spindle end and well.

While the friction between the bushing and handle under the pressure of the spring 21 ordinarily suffices to prevent the bushing from unscrewing from the spindle stud 9, a positive lock may be readily afforded by imparting a plural faced exterior to the expanded end 27 thereof, and similarly shaping its seat 28 at the bottom of the well 15 in the button. It is necessary to displace the handle only slightly with respect to the bushing and against the action of the spring 21, to unseat the bushing end so that it may be freely rotated. Upon release of the handle, the spring again forces it down and re-establishes the engagement between the parts 27 and 28.

Various other modifications in detail, shape and construction of the parts will readily occur to those dealing with the problem, without departing from what I claim as my invention.

I claim—

1. In an electric switch, a rotary switch spindle, an operating handle therefor, means for establishing a rotatively rigid operating connection between the spindle and handle, and means constantly restrained against displacement with respect to the handle for axially adjusting the handle on the spindle while maintaining undisturbed the operating connection between the parts.

2. In an electric switch, a rotary switch spindle, an operating handle therefor having an axially adjustable screw connection therewith, said connection comprising a screw member carried by the handle and constant-

ly restrained against axial displacement with respect thereto, and a rotatively rigid independent operating connection between the handle and spindle maintained in all positions of axial adjustment.

3. In an electric switch, a rotary switch element, a rotatively rigid operating handle engaging the same for simultaneous rotation, and means constantly restrained against displacement with respect to the handle for axially adjusting the handle on the spindle during the maintenance of said operating engagement.

4. A handle for rotary snap switches comprising a member in swivelling engagement with the handle for securing the latter with axial adjustability to a rotary switch spindle and means for normally holding said swivelling member against rotation with respect to the handle.

5. A handle for rotary snap switches comprising a member in swivelling engagement with the handle for securing the latter with axial adjustability to a rotary switch spindle, together with means for insuring operative engagement between the handle and a switch operating member effective in all positions of axial adjustment between the spindle and handle and means for normally holding said swivelling member against rotation with respect to the handle.

6. A handle for rotary snap switches, said handle being recessed to establish a rotatively rigid engagement with a driving element of the switch, in combination with means swivelling with respect to the handle, for securing the handle to a switch spindle.

7. A handle for a rotary snap switch, said handle being recessed to afford a pin and slot engagement with the switch spindle to hold the same against relative rotation, in combination with a ferrule swivelling in the handle and having a screw engagement with the spindle for securing the handle thereto in axially adjustable position.

8. A handle for a rotary snap switch, said handle being recessed to afford a pin and slot engagement with the switch spindle to hold the same against relative rotation, in combination with a ferrule swivelling in the handle and having a screw engagement with the spindle for securing the handle thereto in axially adjustable position, together with a spring between the ferrule and handle for holding the latter in snug engagement.

9. A handle for rotary snap switches, said handle being recessed to receive and engage an operating element for the switch, in combination with means swivelling with respect to the handle, for securing the handle to a switch spindle, and means for normally holding said swivelling means against relative rotation with respect to the handle.

10. A handle for rotary snap switches, comprising a body adapted to engage an

operating element of the switch, a bushing rotatable with respect to the handle for securing it to a switch spindle, means for establishing a non-rotative engagement between the handle and said bushing, and a spring for maintaining said parts in non-rotative relation, said bushing being dis-

placeable against the action of said spring to free the parts for relative rotary movement.

In testimony whereof I have signed my name to this specification.

GEORGE B. THOMAS.
